MULTIPLE-BAR, SELF-DUMPING MOLD

Arthur Fritschle, University City, Mo., assignor
to American Smelting and Refining Company, New York, N. Y., a corporation of New Jersey

Application May 16, 1942, Serial No. 443,874

8 Claims.

(Cl. 22—142)

This invention relates in general to molds and more particularly to a mold for casting small ingots of such metals as babbitt, type metal, solder and the like.

In the commercial manufacture of such ingots, it is customary to use open-top, multi-cavity molds and to use the same mold to cast different kinds of metals. It is customary to provide removable name plates in the molds to cast different names into the ingots of the different metals. It is customary to make such molds in two sections secured together by machine bolts, which sections are not separable for the purpose of dumping the mold, but must be separated for the purpose of changing name plates. Considerable difficulty is encountered in changing the name plates because in use the name plates and the mold sections become battered and deformed. Considerable difficulty is also encountered in removing the cast ingots from the molds for the same reason.

According to the present invention, a separable two-section mold is provided overcoming the above disadvantages and having many additional advantages. Briefly, the new mold, according to a particular embodiment of the invention, comprises a lower section or water bosh having a flat surface constituting a chill plate. The removable name plate is secured within a cavity in the chill plate surface. The upper section comprises a perforate plate-like member having a plurality of mold cavities extending entirely through the section. A suitable spring hinge construction is provided connecting the two sections along one edge and a suitable disengageable clamping arrangement is provided to connect the sections along the opposite edge. Thus, after the metal is cast, the clamping arrangement may be disengaged and the upper section may be raised and swung around its hinge to dump the metal bars from the mold.

The invention also consists in certain new and original features of construction and combinations of parts hereinafter set forth and claimed.

Although the novel features which are believed to be characteristic of this invention will be particularly pointed out in the claims appended hereto, the invention itself, as to its objects and advantages, and the manner in which it may be carried out, may be better understood by referring to the following description taken in connection with the accompanying drawings forming a part thereof, in which,

Fig. 1 is a plan view of the new mold;

Fig. 2 is a vertical transverse section taken on the line 2—2 of Fig. 1;

Fig. 3 is a front elevation of the mold;

Fig. 4 is a horizontal section taken on the line 4—4 of Fig. 2;

Fig. 5 is a vertical section taken on the line 5—5 of Fig. 2;

Fig. 6 is a perspective of one of the ingots removed from the mold;

Fig. 7 is a perspective of one of the removable name plates; and

Fig. 8 illustrates a mold stand and dumping arrangement.

Like reference characters denote like parts in the several figures of the drawings.

In the following description and in the claims, various details will be identified by specific names for convenience, but they are intended to be as generic in their application as the art will permit.

Referring now to the drawings, the mold comprises a lower section or water bosh 10 which may be made in any desired manner as, for example, by steel plates suitably welded together. The water bosh has side walls 11 and 12, front wall 13 and back wall 14; bottom wall 15 and a top wall 18 forming a chill plate. The water bosh may be suitably welded to a base plate 16 which may rest on any suitable support as, for example, a table, indicated by 17.

The top wall 18 has a plurality of recesses 19, each extending from front to back of the mold. A plurality of name plates 20 are removably mounted in these recesses. The individual name plates preferably have straight parallel side walls 45 (see Fig. 7) and a beveled end wall 22 adapted to fit under a corresponding overhanging end wall of its recess 19 (see Fig. 2). The rear end of each name plate is stepped off to provide a flange 23 to engage over the head of a suitable retaining screw or bolt 24 as indicated especially in Figs. 1 and 2. The individual name plates 20 may have suitably raised configurations, or depressed configurations, indicated by 64, so that the trade name or other descriptive matter

may be cast onto the finished ingot. Name plates having the same names or name plates having different names may be used together in the same mold if desired.

If desired, instead of using a plurality of name plates a single large recess may be provided and a single name plate may be provided for a plurality of ingots. The single name plate may have a plurality of the same trade names or a plurality of different trade names as desired. The single large name plate may be held down by a beveled edge on the front side of the mold and by screws on the rear side of the mold and may have straight perpendicular sides as in the smaller individual name plates.

The water bosh 10 has a hollow interior broken up by sets of baffles 24 and 34. The baffles 24 project upwardly from the bottom wall 15 of the mold short of the top wall 18 and extend from the front wall 13 short of the back wall 14 as indicated more particularly in Figs. 4 and 5. The

baffles 34 alternate with the baffles 24 and project downwardly from the top wall 18 short of the bottom wall 15 and project from the back wall 14 short of the front wall 13. A suitable inlet conduit 25 and a suitable outlet conduit 26 are provided.

Cooling fluid, such as water, is circulated by means (not shown) into inlet conduit 25 whence it passes back and forth lengthwise of the baffles 24 and 34 to outlet 26. At the same time a certain amount of water passes over the baffles 24 and under the baffles 34. The baffle plates or fins may be either cast into the water bosh in the case of an iron casting, or they may be made of steel plate welded into proper position in case the bosh is so made. It will be noted that these fins are not only staggered as between front and back walls but are also staggered as between top and bottom walls.

The upper mold section 27 comprises a generally flat steel plate having a back wall 28, a front wall 29, side or end walls 30 and partitions 31 forming a plurality of mold cavities 33 corresponding to the several name plates. The mold cavities have tapered side surfaces 32 on all sides to facilitate removal of the ingots when cast. The end walls 30 and the partitions 31 are thickened toward their middles to minimize difficulties from expansion and contraction.

The upper section 27 may be made of either cast iron or steel, but in either case there may be a tendency for this plate to warp or bend upwardly toward the center rather than at the front and back, since these points are clamped down against the water bosh. It is obvious that this warping should be guarded against since any metal running between the mold sections would cause fins which would delay removal of the ingots from the mold. Thus, reinforcing ribs running from front to back of the mold section will minimize warping or bending difficulties.

The hinge construction for connecting the sections 10 and 27 comprises a series of eye bolts 35 passing snugly through sleeves 36 suitably secured to base plate 16. A plurality of helical springs 39 surrounds bolts 35 and acts between the under side of plate 16 and washers 37 held in place by nuts 38. The screwing of nuts 38 on bolts 35 serves to adjust the tension of springs 39. A plurality of washers 40 surrounds bolts 35 above sleeves 36.

The mold section 27 has a plurality of integral lugs 41 through which a bolt 42 passes, this bolt constituting the pintle for the hinge. This bolt 42 also passes through the eyes 44 of the eye bolts 35 and a nut 43 is threaded on pintle 42 to hold the hinge assembled.

It will be understood that, while the eye bolts 35 fit snugly in the sleeves 36, they are free to move up and down. The close engagement of the end eyes 44 with the end lugs 41 fixes the lateral position of the upper section 27 on the lower section 10 insuring proper register of these sections when they are clamped together for the molding operation. At the same time, the springs 39 help hold the sections together with the proper clamping pressure.

For holding the sections together on the other side of the mold, a disengagable clamping device is provided. A plurality of snubbing lugs 46 are mounted on the bosh 10 and a plurality of lugs 47 are secured to the upper section 27. Links 48 are pivoted to lugs 47 by pivot screws 53 passing through links 48 and screwed into the lugs 47. An eccentric drum 49 having a cam surface 52

is pivoted to links 48 by pins 51 passing through links 48 and screwed into drum 49. A handle 50 is secured to eccentric drum 49. Flaring mold guides 54 are suitably connected to the bosh 10 to guide the upper section 27 and hold it in register.

To promote more efficient use of the mold, the arrangement shown in Fig. 8 may be provided. Here a dumping frame, indicated in general by 60, is connected to the table 17 by a series of hooks 63 on the frame 60 overlying hook 62 on the table 17. A box truck 61 may be wheeled under frame 60 in such position that, when the upper section 27 is moved to the dumping position shown in Fig. 8, the ingots 55 will fall directly into the dump truck 61. The front side of the upper section 27 may fall against the dumping frame 60, as indicated, to help jar loose the ingots.

In operation, to prepare the mold for casting after the previously cast ingots are dumped, the top section is swung from the dumping position, indicated in Fig. 8, to the casting position indicated in Figs. 1 and 2. The drum 49 is engaged under lugs 46 and the handle 50 pressed downwardly to snub the cam surface 52 against lugs 46. The pressure exerted by the eccentric engagement on the one side, and that exerted by the springs 39 on the other, tightly engage the two sections 27 and 10 together. The molten metal is then poured into the mold through the open tops of the mold cavities 33 by a suitable pouring apparatus as, for example, a ladle (not shown), the molten metal being brought flush with the top of the front and back walls 28, 29. After the metal solidifies, the handle 50 is raised and the eccentric drum 49 disengaged from lugs 46 and the entire top section, carrying its cast ingots, is swung to the dumping position shown in Fig. 8 where the impact of the top section falling against the dumping frame 60 helps dislodge the ingots 55 causing them to drop into box 61.

Due to the flaring walls 32 and to the tight contact between mold sections throughout their entire extent preventing the formation of fins, the individual ingots or bars will fall out very readily when swung to the position of Fig. 8. If they do not, a slight tapping on the under side of the ingots (their top side when the top section is in dumping position) will cause the ingots easily to fall out of the mold into a suitable receptacle. The mold is then ready to be clamped together again for an additional pouring operation.

When it is desired to change one or more of the name plates 20 as, for example, to cast a different metal, it is only necessary to move the upper mold section 27 to the dumping position and then remove the few screws 21 and take out the one or more name plates 20 and insert the new name plates.

Thus, a mold is provided which is easy to use, the cast ingots can be easily removed without any troublesome sticking and the name plates can be easily replaced for different metals. Such a mold is particularly advantageous for casting various white metals and alloys as, for example, type metal, solder, antimonial lead, babbitt, etc. This mold is of great advantage where many different brands of ingots are to be cast from a limited number of molds. Otherwise, a different mold would be required for each brand.

Since the ingots do not stick in the molds and since it is easy to remove and replace the name plates, it is not necessary to hammer the mold

sections with hard blows and, hence, they are not deformed. Consequently, no trouble is caused by the molten metal seeping in between the top and bottom sections or under the name plate and anchoring the cast bars.

Increased production is also obtained since the bars are dumped automatically after each successive casting merely by swinging the mold open. Less effort is required on the part of the workmen since it is only necessary to swing the upper mold section (which acts as a skeleton carrier for the cast bars), the heavy water jacket or bosh remaining fixed throughout the entire operation.

The present mold is less expensive to make in that the lower section, being permanently mounted, can be made somewhat lighter and cheaper and the fact that all of the cooling is applied to the lower section, no special cooling means is necessary for the upper section.

While certain novel features of the invention have been disclosed and are pointed out in the annexed claims, it will be understood that various omissions, substitutions and changes may be made by those skilled in the art without departing from the substance of the invention.

What is claimed is:

1. In an ingot mold, a lower, water-cooled section, an upper uncooled plate-like member forming an upper section, a plurality of guides secured to said lower section, rods slidably mounted in said guides, abutments on said rods, springs surrounding said rods between said lower section and said abutments, eyes secured to said rods, said upper section having lugs, a pintle passing through said eyes and said lugs forming a hinge, snubbing lugs secured to said lower section, links pivoted to said upper section, an eccentric drum pivoted to said links, a handle secured to said drum whereby rotation of said drum tightens the engagement between said sections.

2. In a mold, first and second sections, a plurality of guides secured to said first section, rods slidably mounted in said guides, abutments on said rods, springs surrounding said rods between said first section and said abutments, eyes secured to said rods, said second section having lugs, a pintle passing through said eyes and said lugs forming a hinge, snubbing lugs secured to said first section, links pivoted to said second section, an eccentric drum pivoted to said links, a handle secured to said drum, whereby rotation of said drum tightens the engagement between said sections.

3. In a multiple-bar, self-dumping mold for casting babbitt, type metal and the like, a lower section comprising a hollow water bosh having a substantially flat top wall provided with a shallow recess, a name plate in said recess, means for circulating a cooling fluid through said hollow water bosh, an upper section comprising a comparatively thin skeleton-like member having a plurality of mold cavities extending entirely through the section separated by partitions, the side walls of the mold cavities flaring upwardly, hinge means connecting said mold sections along one wall and a clamping device connecting said mold sections along the other wall.

4. In a mold for casting material, a lower section comprising a hollow bosh having a substantially flat top wall provided with a shallow recess, a name plate in said recess, means for circulating a cooling fluid through said hollow bosh, an upper section having a mold cavity extending

entirely through the section, the side walls of the mold cavity flaring upwardly, hinge means connecting said mold sections along one wall and a clamping device connecting said mold sections along the other wall.

5. In a two-part mold, a lower section comprising a hollow water bosh having top and bottom walls connected by side walls, alternating upper and lower baffles in said bosh, said upper baffles extending downwardly from said top wall short of said bottom wall, said lower baffles extending upwardly from said bottom wall short of said top wall, said upper baffles also extending from a first of said side walls short of the opposite side wall, said lower baffles extending from said opposite side wall short of said first side wall, inlet and outlet conduits connected to said water bosh at opposite sides thereof, whereby to cause circulating water to pass through the bosh back and forth lengthwise of said baffles and over and under said baffles, and an upper mold section cooperating with said lower section.

6. In a two-part ingot mold, a lower section constituting a chill plate, fluid means for cooling said lower section, an upper section comprising a comparatively thin, skeleton-like member adapted to rest on said chill plate and having a plurality of open-top mold cavities extending entirely through the section, said chill plate forming the bottom of the mold when the sections are together, hinge means connecting said sections along one edge, the hinge axis being parallel to the plane of the chill plate, means for swinging said upper section away from said lower section after the metal is cast whereby the cast ingots may be jarred loose from said upper section through the top open face thereof.

7. In a two-part ingot mold, a lower section constituting a chill plate, fluid means for cooling said lower section, an upper section comprising a comparatively thin, skeleton-like member adapted to rest on said chill plate, said upper section having a back wall, a front wall, side walls connecting said back and front walls, partitions connecting said back and front walls and disposed between said side walls, said walls forming a plurality of open-top mold cavities extending entirely through the section, said chill plate forming the bottom of the mold when the sections are together, hinge means connecting said sections at said back wall, a removable clamping device connecting said sections at said front wall, said end walls and partitions being vertically thickened intermediate their lengths to minimize warping of the upper section.

8. In a mold for casting ingots, a lower section comprising a hollow bosh having a substantially flat top wall provided with a shallow recess, said recess having one wall thereof undercut, a four-sided name plate seated in said recess and having one side portion seating under said undercut wall, said name plate having on its opposite side a recessed portion, a screw having a head engaging over said recessed portion and threaded into said top wall, said name plate being liftable out of the top face of said recess upon disengagement of said screw with said name plate, a removable upper section having a mold cavity whose bottom wall is formed by said name plate, and means for removably clamping said sections together.

ARTHUR FRITSCHLE.
